UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,356,592.

Specification of Letters Patent. Patented Oct. 26, 1920.

Application filed November 22, 1917. Serial No. 203,355.

To all whom it may concern:

Be it known that I, JOHN H. BELL, a citizen of the United States, residing at South Orange, in the county of Essex and State of New Jersey, have invented certain new and useful Improvements in Telegraph Systems, of which the following is a full, clear, concise, and exact description.

This invention relates to telegraph systems, and more particularly to systems of duplex telegraphy.

The principal object of this invention is to provide an improved system to prevent interference with telegraphic receiving devices due to the effects which usually arise through mutual induction between neighboring conductors and a telegraph line circuit.

A further object of this invention is to provide a system of secret service to prevent the possibility of a line circuit being "tapped" by unauthorized parties.

In telegraph working, it is well understood that when a telegraph line parallels other telegraph lines, and also power circuits operated at so-called high potentials, inductive effects from the telegraph circuits and the power circuits may become accumulative in acting inductively on the telegraph circuit. In certain situations such inductive disturbances are sufficient to mutilate or perhaps cause the telegraphic receiving devices to entirely fail in the proper translation of message signals.

In accordance with the present invention there is provided a so-called vibrating or self-aiding electroresponsive receiving device together with current impedance means and current drainage means whereby currents extraneous to the message impulses are deflected from the impulse receiving devices.

In carrying out the so-called secret service feature of this invention the characteristics of the equipment described permit a source of alternating current to be connected in derived relation from a main telegraph line in such a manner that the alternating currents may divide and pass from the line circuit to ground at each terminal station. Therefore, in case the line were tapped by means of ordinary telegraphic equipment, the alternating currents being superimposed on the regular message currents which traverse the line circuits, they would cause such

receiving devices to respond and accordingly it would not be possible to distinguish or read the telegraphic signals.

This invention is illustrated diagrammatically in the accompanying drawing, in which, for the sake of clearness, only so much of a telegraphic equipment has been shown as will be necessary to a clear understanding of this invention.

In the drawing, Figure 1, is shown a line completely equipped in accordance with this invention, while Figs. 2 and 3 illustrate respectively alternate arrangements of the equipment shown in Fig. 1.

In describing the operation of this system, let it be assumed that the reference characters A and B represent terminal stations joined by a main line conductor L and since a clear understanding of the system may be had through a description of operations by which messages may be transmitted between the two stations, a message originating at the station A will first be traced. A telegraph transmitting key 1 normally connects a negatively poled and grounded battery 2 with the apex of a bridge duplex formed by resistance units 4 and 5, a polar relay 10, an artificial line AL and the main line L. Current from the source 2 accordingly divides, one portion traversing the resistance 5 and the artificial line AL to earth, while a like portion traverses the resistance unit 4, the line L, the windings 31 and 32 of a polar relay 30 at the station B, an impedance unit 27 and an artificial line AL to earth. A portion of the current arriving at the station B also traverses a resistance unit 26 which is connected in parallel with the windings 31 and 32 of relay 30 and the impedance 27. As well understood in the art, no difference of potential is set up by this current at the points on the line L and the artificial line AL at which the circuits of the receiving relay 10 are connected. Therefore, these outgoing currents are non-effective in this relay. The negative current traced biases an armature 37 of the relay 30 to connect with the grounded source of negative current 38, from which point a circuit may be traced through the winding 33 of the relay 30 and a resistance unit 35 to earth. A condenser charging circuit may also be traced from the armature 37 through the winding 34 of this relay and a condenser 36

100 to connect with the grounded source of negative current 38, from which point a circuit may be traced through the winding 33 of the relay 30 and a resistance unit 35 to earth. 105 A condenser charging circuit may also be traced from the armature 37 through the winding 34 of this relay and a condenser 36

to earth. A conductor 40 may be considered as extending from the armature 37 to a telegraph sounder or other suitable electro-responsive device on which telegraphic impulses may be manifested.

At the station A, when the key 1 is depressed, the negative battery 2 is disconnected and a positively poled line battery 3 connected to the duplex line to traverse the circuits already traced for the first negative current. At the relay 30, the positive current causes the armature 37 to disconnect the battery 38 and to complete a circuit with a grounded source of positive current 39. At the instant the armature 37 severs the connection with the battery 38 and before it reaches the contact corresponding with the battery 39, the condenser 36 will discharge through the windings 34 and 33 of this relay and the resistance unit 35 to earth. The direction of this discharge being cumulative with the action of the positive current through the windings 31 and 32, operation of the relay 30 is, therefore, accelerated by the discharge force which aids in moving the armature 37 to connect with the battery 39. In the last mentioned position of the armature the condenser 36 will receive a charge of positive current, while steady current of like polarity will be connected through the winding 33 and the resistance 35 to earth. It may be pointed out that on the instant the armature 37 engages either one or the other of its contact stops, the action of steady current through the winding 33 will be neutralized by the effect of the condenser charging current through the winding 34, thereby leaving the armature 37 entirely under influence of the current which may be present in the windings 31 and 32, thus insuring that a firm contact will be effected for a sufficient period to properly operate the receiving equipment assumed as connected to the conductor 40. After the condenser 36 has become fully charged, the steady current in the winding 34 acts in opposition to correspondingly poled signaling current in the windings 31 and 32 to the extent that the force of the biasing effect on the armature 37 is relieved, thereby permitting it to respond more readily to the next inversely poled impulse of signaling current.

From the foregoing description, it will be clear that in response to changes in polarity set up in the line conductor L by means of the transmitting key 1, the receiving relay 30 at the station B will respond to connect correspondingly poled currents with the receiving lead 40. The frequency of the current changes set up by the key 1 is sufficiently low not to be seriously affected by the inductance of the impedance 27 and the windings 31 and 32 of the relay 30. Therefore, the telegraphic currents may to

a predetermined extent divide through this relay circuit and the parallel circuit formed thereon by the resistance 26.

In the case of extraneous or induced currents which may be set up in the line L 70 by adjacent telegraph lines or power circuits as already mentioned, the relatively high frequency of the induced currents cause them to seek the path formed through the resistance 26 and the resistances 24 and 25, rather than the circuit formed through the windings of the relay and the impedance coil 27. This invention also provides that, in view of the extreme sensitiveness of the receiving relay 30, due to its self-aiding effects as already pointed out, the bridge arms of the duplex circuit, as the resistances 24 and 25 at the station B and the resistances 4 and 5 at station A, may each be of relatively low resistance and this is also true of the resistances 6 and 26. Therefore, in addition to traversing the resistance unit 6 or 26, disturbing currents also find a path through the bridge resistance units 4 and 5 for the station A, and 24 and 25 for the station B to earth through the artificial line.

Referring to the matter of the secret service features of this system, an alternating current generator 41 is shown legged or connected in branch relation from the main line conductor L to earth. Currents produced by this generator traverse the main line to the station B and, due to the arrangement of shunts thereat, are deflected from the receiving circuits of the polar relay 30 to traverse the resistance unit 26 and the bridge arm resistances 24 and 25 to earth through the artificial line AL. A portion of the currents from the generator 41 also traverse the main line to the station A, thence continuing over the corresponding circuits, as the resistance 6 and the bridge arm resistances 4 and 5, through the artificial line to earth at that point. The frequency of the currents from the generator 41 should be sufficiently high to cause no appreciable effect on the operating circuits of receiving relays 10 or 30 at the terminal stations.

Since the equipment at the station A is typical of the equipment at the station B it will be obvious that operation of the transmitting key 21 at the latter station would alternately connect a source of negative current 22 and a source of positive current 23 with the duplex line and these current changes on arriving at the station A continue through the windings 11 and 12 of a polar relay 10 to correspondingly control an armature 17, whereby oppositely poled sources of current 18 and 19 may be applied to the conductor 20 to control a suitable telegraph receiving equipment (not shown). The windings 13 and 14 of the re-

lay 20, together with a condenser 16 and a resistance unit 15, from the self-aiding circuits for this relay, which operate in a manner similar to that already described for the self-aiding circuits of the relay 30.

The arrangement shown in Fig. 2 of the drawing differs from the arrangement already described only in the omission of the resistance unit 6, to compensate for which it is contemplated that the bridge arm resistances 4 and 5 would be of a sufficiently low value to properly drain inductive or non-message currents from the receiving circuit of the relay 10.

In describing the alternate arrangement shown in Fig. 3, it will be noted that the circuit arrangement is a combination of the bridge duplex and the differential polar duplex, since the apex or outgoing connection point of the bridge arm resistances 4 and 5 is also connected to the neutral point intermediate the windings 11 and 12 of the polar relay 10. An impedance coil 28 interposed between the exterior terminal of the coil 11 and the line conductor L therefore establishes this winding in a series which parallels the bridge resistance 4, while the impedance coil 7 connected in series with the winding 12, thence to the artificial line AL establishes the latter winding in a series paralleling the bridge arm resistance 5. It will be obvious that induced currents or secret service currents from the line L would readily pass through the bridge resistances 4 and 5 and the artificial line AL to earth, while the impedance units 21 and 7 would render the receiving circuit of the relay 20 substantially opaque to such currents, but responsive, however, to message currents due to the relatively low frequency of the latter. In this arrangement the self-aiding circuits of the polar relay 20 are typical and work in the same manner as the self-aiding circuits described in connection with the other figures of the drawing.

What is claimed is:

1. A telegraph system comprising a main line, an artificial line, polar duplex equipment for said lines, means for transmitting impulses over said lines at a substantially predetermined frequency, self-aiding relay means for the reception of said impulses, and means including an inductance and resistance for rendering said receiving means non-responsive to current of a frequency relatively higher than the frequency of said signal impulses.

2. In a telegraph system, a main line, an artificial line, bridge duplex equipment employing ratio arms for said lines, means for the transmission of signaling impulses at a predetermined rate or frequency over said lines, self-aiding relay means to form a polar duplex arrangement with respect to said lines for the reception of said impulses, inductive means connected intermediate said relay means and said main and artificial lines respectively for deflecting a portion of the current of said impulses from said impulse receiving means to be drained through the arms of said bridge duplex.

3. In a telegraph system, a main line, a duplex equipment comprising a combination of bridge and differential polar duplex equipments, means for transmitting impulses over said line at a relatively predetermined speed or frequency, a self-aiding polar relay for the reception of said impulses, means to render said impulse receiving means unresponsive to current changes on said line circuit of higher speed or frequency than said signaling impulses and to cause said high frequency current changes to be deflected through the arms of said bridge duplex equipment.

In witness whereof, I hereunto subscribe my name this 20th day of November, A. D., 1917.

JOHN H. BELL.
